UNITED STATES PATENT OFFICE.

ERNEST H. SCHMIDT, OF CLEVELAND, OHIO, ASSIGNOR TO THE NATIONAL MALLEABLE CASTINGS COMPANY, OF CLEVELAND, OHIO, A CORPORATION OF OHIO.

FRICITION DRAFT-RIGGING.

1,192,570.

Specification of Letters Patent. Patented July 25, 1916.

Application filed March 11, 1912, Serial No. 683,035. Renewed February 17, 1916. Serial No. 78,961.

To all whom it may concern:

Be it known that I, ERNEST H. SCHMIDT, a citizen of the United States, residing at Cleveland, Cuyahoga county, Ohio, have invented a new and useful Friction Draft-Rigging, of which the following is a specification, reference being had to the accompanying drawings, in which—

Figure 1 is a plan of my improved draft 10 rigging, showing its application to a railroad car; Fig. 2 is an elevation thereof; and Fig. 3 is a section on lines III—III of Fig. 2. Figs. 4 and 5 are details of Fig. 3, and Fig. 6 is a section on lines VI—VI of Fig. 15 3. Figs. 7 and 8 are sections showing modified forms of my invention.

My invention relates to an improvement in friction draft rigging, and is particularly designed for use with the heavy rolling stock 20 now in service on the railways. The draft rigging of my invention absorbs and dissipates to a very high degree the shocks of buffing and draft by reason of the frictional engagement of its parts, and reduces the 25 damaging recoil shocks which are inherent in draft riggings now in use.

Referring to the drawings: 2 indicates a longitudinally extending friction member or casing, preferably cylindrical in form. The 30 case 2 has an enlarged portion 3 preferably formed integral therewith, which is rectangular in form, and which is adapted to abut against the draft sill stops 4 which are attached to the draft sills 5 of the car structure. Seated within the rear of the casing 35 5 is the compression spring 6 and the release spring 7, the spring 7 being preferably located within the spring 6, and both of which abut at their rear ends against the rear end 40 of the casing or friction member 2.

The forward end of the spring 6 bears against the flat face of the rearmost cone ring 8 which is preferably in the form of a single truncated cone. Forwardly of this 45 cone ring 8 are the cone rings 9 which are preferably in the form of double truncated cones, and a single truncated cone 10 which bears against the front follower 11. The cones 8, 9 and 10 are spaced apart by a plurality of segmental rings 12. The conical or wedging face of each cone is in bearing engagement with the corresponding conical faces of the adjacent segmental rings.

In my preferred construction I show the 55 co-acting bearing faces of the cones and the

segments inclined at unequal angles, the angle of the inner bearing faces of the cones being more acute than those of their outer bearing faces, so that the inner faces will act more efficiently to transmit by wedging 60 pressure upon the co-acting surfaces of the segments the movement of the parts so that there will be produced a wedging frictional engagement between the exterior surfaces of the segment and the interior surface of the 65 case 2. The less acute forward faces of the cones and the co-acting rear surfaces of the segments also admit of a freer releasing movement, and tend to prevent the cones and segments from sticking together during 70 the releasing action.

The front follower 11 preferably has a boss 13 extending centrally through the foremost cone ring 10. The releasing member 14 is preferably located centrally in and 75 passes through the series of cones and segments, and bears at its forward end against the boss 13 of the follower 11. Near its rear end this member 14 has a bearing ring 15 against which the forward end of the 80 spring 7 abuts. The releasing member 14 is provided with a series of annular grooves 16 adapted for the reception of split rings which form abutments 17 thereon. The bearing ring 15 and abutments 17 are adapted 85 to strike the inner shoulders 18 of the cones 9, and release their wedging engagement with the co-acting segmental rings 12.

The outer end 19 of the follower 11 is preferably rectangular in form and of the 90 same general outline as the rear end of the casing 2, and bears against the forward draft sill stops 20.

21 is the usual form of yoke and is secured to the coupler-butt 22 of the coupler 23.

For a bearing surface for the segmental rings 12, I prefer to employ a hardened steel insert or bushing 24, which is forced into the casing and is retained therein by the 100 plate 25. The casing 2 is preferably reinforced toward its forward end to provide against bursting strains.

The operation of the draft rigging is as follows: When the coupler receives a buffing 105 shock, this shock is transmitted from the coupler-butt 22 to the front follower 11, which is caused to move rearwardly and to enter the casing 2, the rear end of the casing being held from rearward movement, rela- 110

tive to the car, by the rear stops 4, which are attached to the draft sills 5. The follower 11 transmits this pressure, through the cone 10, by a wedging action to the foremost segmental ring 12, and this pressure is transmitted from one to the other throughout the entire series of cones and segmental rings, and the entire series is caused to move rearwardly within the casing 10 as the cone 10 and the front follower 11 enter the forward end of the casing. The rearward movement of the series of segmental rings and cones is resisted by the spring 6 which bears against the rear end 15 of the innermost cone 8, and this resistance is transmitted through the cone 8 to the cones 9 and segments 12 causing a powerful frictional engagement between the exterior surfaces of these segmental rings 12 and the entire cylindrical surface of the casing, thus exhausting the force of the buffing shock. This frictional engagement of the segments and the interior surface of the casing increases progressively, since, as the cones and 25 segments move rearwardly in the casing, the spring 6 bears with increasing pressure on the rearmost cone 8 and this pressure is transmitted thereby to the other cones and frictional members as described.

30 When the coupler 23 is under draft the shock is transmitted through the coupler-but 22 and the yoke 21 to the casing 2, causing it to move forwardly. As the front follower 11 is held against forward movement 35 by the forward draft sill stops 20, the forward action of the casing 2 is resisted by the spring 6 which forces into wedging engagement the cones 8, 9 and 10 and the segmental rings 12, causing the same relative 40 movement and progressively increasing frictional engagement between the segments and the casing as when the draft rigging is under the buffing shock.

After buffing or draft the releasing action 45 of the spring 7 drives the member 14 forwardly and with it the front follower 11, thus releasing the wedging engagement between the outermost cone 10 and the adjacent segmental ring 12. The bearing 15 and the abutments 17 are preferably so spaced along the releasing member 14 that they successively strike the succeeding shoulders 18 of the cones 9 and release their wedging engagement with the corresponding segmental rings 12, until finally the bearing 15 strikes the rearmost cone shoulder 18 and releases the rearmost of the cones 9 from wedging engagement with the co-acting segmental ring and the parts including 55 the coupler are restored to normal position.

In Fig. 7 I show a modification of my invention in which the cones 8' and 9' are apertured for admission of the inner spring 65 7', which acts as the releasing means and

extends from end to end of the casing. This spring 7' abuts against the face 26 of the front follower 11', which is shaped so as to co-act with the forwardly inclined surface of the foremost segment 12'. In this form 73 the bushing 24' is secured by the rivets 27 to the casing 2'.

A further modification of my invention is illustrated in Fig. 8, in which the cone 8' is apertured for admission of the inner 75 spring 7' which abuts against the rear face 28 of the intermediate cone 9', so that the spring 7' will act directly to relieve the pressure on the rearmost segment 12' and the springs 14' will act to relieve the pressure 80 on the other segments 12', after buffing or draft.

It is obvious to those skilled in the art that many changes may be made in the form or arrangements of the various parts which 85 I have described without departing from my invention, since what I claim is:

1. In frictional shock absorbing mechanism, a longitudinally-extending friction member, a plurality of sets of friction shoes 90 in frictional engagement with said friction member, a plurality of wedging members in wedging engagement with said shoes, said wedges and sets of shoes being arranged alternately and in tandem, means including the wedges for transmitting pressure to said friction shoes, a compression spring, and a release spring, said release spring having at one end a bearing against an abutment fixed relative to the longitudinally-extending friction member and reacting at its other end against a member more remote from the compression spring than the set of shoes nearest the compression spring, to relieve the wedging pressure between a wedge and a set of shoes. 95

2. In frictional shock absorbing mechanism, a longitudinally-extending friction member, a plurality of sets of friction shoes in frictional engagement therewith, wedging members in wedging engagement with said shoes, said wedges and sets of shoes being arranged alternately and in tandem, a compression spring, a release spring, and a releasing member co-operating 110 with said release spring, said releasing member having shoulders spaced apart and adapted to engage the wedge members to release the wedging engagement between said members and sets of shoes. 115

3. In frictional shock absorbing mechanism, a longitudinally-extending friction member, a plurality of sets of friction shoes in frictional engagement with said friction member, wedging members in wedging engagement with said shoes, said wedges and sets of shoes being arranged alternately and in tandem, a compression spring, a release spring, and a releasing member co-operating 125 with said release spring, said releasing mem- 130

ber having shoulders spaced apart and adapted to engage the wedging members successively, beginning with that wedge which is farthest removed from the compression spring, to release the wedging engagement between said wedges and sets of shoes.

4. In, frictional shock-absorbing mechanism, a longitudinally-extending friction member, a follower, a plurality of sets of friction shoes in frictional engagement with said friction member, a plurality of wedging members in wedging engagement with said shoes, said wedges and sets of shoes being

arranged alternately and in tandem, a compression spring and a release spring, said 15 release spring having at one end a bearing against an abutment fixed relatively to the longitudinally-extending friction member and reacting at its other end against the follower to relieve the wedging pressure 20 between the wedges and sets of shoes.
